METHOD AND APPARATUS FOR SURFACE CONDITIONING WIRE AND THE LIKE

Norman H. Nye, Cuyahoga Falls, and Edwin J. McIlvried, Akron, Ohio, assignors to The Vaughn Machinery Company, Cuyahoga Falls, Ohio, a corporation of Ohio

Application April 10, 1942, Serial No. 438,454

7 Claims. (Cl. 51—112)

This invention relates as indicated to the surface conditioning of wire and the like and more particularly to the grinding and polishing of the surface of wire and rod.

It is often highly desirable that wire and small diameter rod be produced having a very smooth and highly polished surface. Such uniformity of surface is particularly beneficial in the case of wire cable and the like since any surface flaw or defect in a strand will cause concentration of stress and strain at such point with resultant early fracture. Specifications for wire cable, particularly for such uses as the operation of airplane controls, are becoming progressively more strict. Surface flaws may also operate to limit the degree of reduction to which the wire may be subjected at a single draft without snapping. Various other objections to surface irregularities will be readily apparent and have long been known to those skilled in the art. One common cause of non-uniform surface in the finished product is found in the preliminary drawing of the rod stock to round the same. Small projections on the surface of the rod are upset and elongated while being pressed into the surface of the rod by action of the die. As the wire is progressively reduced, such embedded slivers of metal are likewise elongated and their presence may be determined upon fracture of the wire whereupon they appear as a fuzz or fringe about the broken end. A wire having a smooth and uniform surface will, on the other hand, break cleanly.

Various grinding and polishing devices have been designed to polish the surface of wire and the like, but all such machines have involved obvious disadvantages. Included among such disadvantages are the slowness of travel of the wire therethrough, often only at the rate of about 12 feet per minute; the complex nature of the machine, which usually involves grinding means operative to revolve about the wire while at the same time polishing the same; and the relatively high cost of such machines.

It is, therefore, a primary object of our invention to provide a new method and apparatus for surface conditioning wire, diameter rod, and the like, which will be relatively simple of operation and low in cost.

Another object is to provide apparatus operative to grind and polish the surface of such work at a much higher rate than that previously obtainable.

Still another object of our invention is to provide means for rapidly and effectively grinding and polishing rod after the latter has been

circularized but prior to subsequent reduction by drafting to smaller sizes.

Other objects of this invention will appear as the description proceeds.

- 5 To the accomplishment of the foregoing and related ends, said invention, then, consists of the means hereinafter fully described and particularly pointed out in the claims, the annexed drawings and the following description setting forth in detail certain means and one mode of carrying out the invention, such disclosed means and mode illustrating, however, but one of various ways in which the principle of the invention may be used.
- 15 In said annexed drawings:
- Fig. 1 is a general top plan view of the apparatus of our invention;
- Fig. 2 is a side elevational view of such apparatus;
- 20 Fig. 3 is an enlarged detail view of the grinding and polishing machine showing means for oscillating the wire;
- Fig. 4 is a fragmentary view of such grinding means showing a portion of the wire oscillating
- 25 means in section;
- Fig. 5 is a detail view showing an alternative type of grinding wheel; and
- Fig. 6 is a detailed sectional view of another form of wire oscillating means in which the wire
- 30 gripping means comprises a die.
- Referring now more specifically to such drawings, Fig. 1 shows a plurality of mechanisms, properly arranged relatively to each other for the carrying out of the method of our invention although for convenience shown positioned in closer sequence than would be the case in actual use. The wire or rod 1 is taken from let-off reel 2 and may then pass through a conventional straightening machine 3 before being led through the oscillating head 5 and passed between grind wheels 6 and 7. The wire or diameter rod then passes through a guide 8 and is wound on take-up reel 9 driven by an electric motor 10. The primary features of our invention reside in the oscillating means and grinding means and such devices will now be described in detail.

- The aforesaid oscillating means comprises an oscillating head 5 secured to tubular shaft 11 rotatably mounted in the upper end of stand 12. The other end of hollow shaft 11 is provided with a gear 13 in running engagement with a larger gear 14 rotatably mounted on stand 12. A crank 15 connects gear 14 to the end of eccentric arm 16 adapted to be rotated by motor 17, the length of such arm being less than the radius of gear

14. As a result, when arm 16 is caused to revolve, crank 15 will operate to rock gear 14 back and forth without causing complete rotation thereof (therefore a gear segment may be employed if desired). Rocking of gear 14 causes rocking of gear 13 and oscillating head 5.

Oscillating head 5 carries a pair of pinch rollers 18 and 19, the latter being carried by a rod 20 vertically slidably mounted in said head. A screw 21 and lock nut 22 are provided to adjust the pressure with which roller 19 is urged toward roller 18. The wire 1 passes through tubular shaft 11 and is tightly gripped by pinch rolls 18 and 19 (see Fig. 4). Thus oscillation of head 5, as above described, will cause wire or rod 1 to be likewise oscillated or twisted. When using grinding means of the type next described below, the wire should be turned through at least 180° at each oscillation so that its entire surface will be properly ground. It is contemplated that such oscillations may be at the rate of 1000 per minute or more. When a straightening machine is employed, as shown in Figs. 1 and 2, the torsion will be in the length of wire between such machine and the take-up reel 9. These devices should therefore be sufficiently spaced to distribute the torsion along a considerable length of wire, thereby avoiding any permanent set or injury to the same.

The grinding means may, as above noted, comprise two grinding wheels 6 and 7 rotatably carried by mounts 23 and 24 respectively. Their faces overlap somewhat, as best shown in Figs. 2 and 4 and they are adapted to be driven by motor 25, wheel 6 through pulley 26 and band 27 and wheel 7 through pulley 28 and band 29. The opposing faces of such wheels may be of any suitable abrasive such as emery or the like. Wire or rod 1 passes between the overlapping portions of such wheels and the entire surface of the work is ground and polished as it rapidly oscillates while being drawn through. One or both of the wheels 6 and 7 may be axially adjustably mounted to ensure proper engagement with the work.

In Fig. 6 a detail sectional view is shown of an oscillating head of different type than head 5 above described. In this embodiment a die 30 is employed instead of pinch rolls 18 and 19, the grip of the die being sufficient to rotate the rod or wire as shaft 11 is oscillated, while at the same time bringing about a reduction of the diameter of the work.

In Fig. 5 peripherally grooved grinding wheels 31 and 32 are illustrated in place of wheels 6 and 7. In this embodiment the wire or rod 1 passes between the aligned wheels which, because of the grooves, engage a larger proportion of the surface of the work than is the case with wheels 6 and 7. It is therefore not necessary to rotate the wire to so great a degree to obtain equally complete coverage of the surface.

It will be seen from the foregoing that each of the objects of our invention has been achieved in a simple manner involving no complex machinery and capable of operation at a higher rate of travel of the work. Our novel apparatus is particularly suited to the treatment of rolled rod (such as $\frac{1}{8}$ inch rod) which may, if the Fig. 6 embodiment be employed, be both drawn round and ground in the same operation. Further drafts may then be made and the final product will have a smooth and uniform surface without the necessity of further grinding and polishing. Such improvement of surface results in similarly improved tensile strength of the final product, making the same particularly suitable for use in high grade wire cable and the like.

It will furthermore be noted that our new method involves an entirely novel principle of surface grinding, namely rapid rotative oscillation of a portion only of the length of the work, the torsion being spread along such length. As one result, the wire or rod may be passed through the grinding machine at a greatly increased rate of speed, for example 100 feet per minute. It will, of course, be obvious that various types of grinding mechanisms and oscillating devices other than those specifically illustrated and described may be employed if arranged to cooperate in accordance with the teachings of our invention.

As employed herein and in the claims the term "grinding means" is intended to include any of the means regularly employed to grind, smooth, or polish metal surfaces. The term "wire" is likewise used broadly to designate wire, rod, and elongated rod generally, and more particularly of circular cross-section.

Other modes of applying the principle of our invention may be employed instead of the one explained, change being made as regards the means and the steps herein disclosed, provided those stated by any of the following claims or their equivalent be employed.

We therefore particularly point out and distinctly claim as our invention:

1. In apparatus for surface conditioning wire and the like, means for continuously advancing such wire from a supply coil to take-up means, gripping means operative to grip such wire intermediate said coil and take-up means, means for rapidly rotatively oscillating said gripping means about the axis of such wire to torsionally oscillate an intermediate length only of such wire, and grinding means adapted to contact with such oscillating wire, the degree of oscillation being sufficient to ensure conditioning of the complete peripheral surface of such wire.

2. In apparatus for surface conditioning wire and the like, means for continuously advancing such wire from a supply coil to take-up means, opposed roller gripping means operative to grip such wire intermediate said coil and take-up means, means for rapidly rotatively oscillating said gripping means about the axis of such wire to torsionally oscillate at an intermediate length only of such wire, and grinding wheels having overlapping faces respectively adapted to contact opposite sides of such wire passing therebetween, the degree of oscillation being sufficient to ensure conditioning of the complete peripheral surface of such wire.

3. In apparatus for conditioning wire and the like, means for continuously advancing such wire from supply to take-up, a device including opposed gripper rolls adapted to define the path of travel of and frictionally engage such wire at a point aligned with and lying between such supply and take-up, means for rapidly oscillating said device about the axis of such wire, whereby the length of wire between such supply and take-up is correspondingly oscillated, and grinding means adjacent said device adapted to contact such wire.

4. In apparatus for conditioning wire and the like, means for continuously advancing such wire from supply to take-up, a device including a reducing die for such wire located at a point aligned with and lying between such supply and take-up, means for rapidly oscillating said device about the axis of such wire, whereby the length of wire between such supply and take-up is correspondingly oscillated, about its axis by contact between

the reducing die and the wire, and grinding means adjacent said device adapted to contact such wire.)

5. The method of conditioning wire and the like, which comprises the steps of continuously advancing said wire from supply to take-up, engaging said wire, intermediate said supply and take-up, with gripping means in such manner that there is sufficient friction to move said wire arcuately and insufficient friction to prevent said advancing thereof, rapidly oscillating said gripping means about the axis of said wire and conditioning the entire peripheral surface of said wire by engaging the same with grinding means while being thus oscillated.

6. The method of conditioning wire and the like, which comprises the steps of continuously advancing said wire from supply to take-up, engaging said wire, intermediate said supply and take-up, with gripping means in such manner that there is sufficient friction to move said wire

arcuately and insufficient friction to prevent said advancing thereof, simultaneously reducing the cross section of said wire as it is gripped, rapidly oscillating said gripping means about the axis of said wire and conditioning the entire peripheral surface of said wire by engaging the same with grinding means while being thus oscillated.

7. In apparatus for surface conditioning wire and the like, means for continuously advancing such wire from a supply to take-up means, gripping means operative to grip such wire intermediate said supply and take-up means, means for rapidly rotatively oscillating said gripping means about the axis of such wire, and mechanical surface conditioning means adapted to contact with such oscillating wire, the degree of oscillation being sufficient to ensure conditioning of the complete peripheral surface of such wire.
